UNITED STATES PATENT OFFICE.

ELMER E. FOX, OF MASSILLON, OHIO.

TIE PLATE.

Application filed May 16, 1921. Serial No. 469,793.

To all whom it may concern:

Be it known that I, ELMER E. FOX, a citizen of the United States, residing at Massillon, in the county of Stark and State of Ohio, have invented a new and useful Tie Plate, of which the following is a specification.

This invention relates to railroad tie plates such as are attached to the upper surface of a tie and support the rail, and has for its objects to provide a tie plate arranged to be spiked or otherwise fixedly mounted upon the top of a wooden tie and provided with means for clamping opposite sides of the base flange of the rail, the clamping means being so constructed as to prevent spreading and creeping of the rails; other objects being the provision of a tie plate which may be used in conjunction with a tie rod as shown in my Patent No. 1,349,754 of August 17, 1920, to provide a metallic tie especially adaptable for use in mines or industrial work.

The above and other objects may be attained by forming the tie plate from a single plate of steel or the like having tangs stamped upwardly from diagonally opposite corner portions thereof, said tangs being arranged to clamp opposite sides of the base flange of a rail, the edges of the tangs being preferably sharp in order to bite into the base flange of the rail to prevent creeping, oppositely disposed apertures being provided in the plate for the reception of spikes or the like for attaching the plate to a wooden tie, or for the attachment of a tie rod.

The invention thus set forth in general terms is illustrated in the accompanying drawings forming part hereof in which—

Figure 1 is a perspective view of a tie plate embodying the invention;

Fig. 2, a plan view of the plate showing the initial position in which the same is placed for attachment to a rail;

Fig. 3, a plan view of a section of rail showing a tie plate connected thereto and mounted upon a tie;

Fig. 4, a section on the line 4—4, Fig. 3, on a larger scale;

Fig. 5, a perspective view of a slightly modified form of plate especially adaptable for use in mines or industrial roads;

Fig. 6, a cross sectional view showing the connection of a tie rod to the plate to form a metallic tie; and

Fig. 7, an enlarged cross sectional view through a portion of the plate, showing the sharpened edge upon the tang.

Similar numerals of reference indicate corresponding parts throughout the several figures of the drawings.

A practical embodiment of the invention is disclosed in the accompanying drawings forming a part of this specification in which similar numerals of reference indicate corresponding parts throughout the several views.

Referring first to Figs. 1 to 4 inclusive, the rectangular metallic tie plate is indicated generally at 1 and is provided at diagonally opposite corner portions with the tangs 2 which are cut out from the body portion of the plate and formed to extend over opposite sides of the base flange 3 of the rail, the inner edge of each tang being sharpened as at 4 in order to bite into the base flange of the rail as best shown in Fig. 4 to clamp the rail firmly upon the tie plate and prevent creeping of the rail. This sharpened edge is best shown in the enlarged view of the tang in Fig. 7 and is obtained by the peculiar manner in which the tangs are stamped from the tie plate, producing a sharpened lower edge upon the forward end of each tang which actually bites into the base flange of the rail and positively prevents creeping of the rails.

A pair of diagonally opposite apertures 5 is formed upon each side of the tie plate for the reception of spikes or the like for attaching the tie plate to a wooden tie. In attaching the plate to the rail, it is first placed in the position shown in Fig. 2, the tangs 2 engaging the base flange of the rail upon opposite sides, the tie plate being set diagonally with reference to the rail and then driven, with a hammer or the like, into positive clamping position upon the rail as shown in Fig. 3, the tangs firmly gripping opposite sides of the base flange and owing to the sharpened edges thereof biting into the base flange of the rail, preventing longitudinal movement of the rail with reference to the tie plate.

The tie plate is then mounted upon a wooden tie as shown at 6, as by the spikes 7 driven through the apertures in diagonally opposite corners of the tie plate. The rail is thus firmly clamped upon the tie plate which is positively connected to the tie, the rail being held against creeping by the tangs 2

upon the tie plate, and as these tangs engage the base flange of the rail upon opposite sides, the possibility of the rails spreading is reduced to a minimum, the tie plate 5 also serving as a brace for the rail upon curves.

In Figs. 5 and 6 is illustrated a slightly modified form of the invention especially designed for a smaller tie plate particularly 10 adapted for use in mines or industrial roads. In this form of the invention the plate 1^a is preferably smaller in dimensions and may be made of lighter material, the tangs 2^a being located closer together as they are 15 adapted to receive a lighter rail and the apertures 5^a are preferably located in the longitudinal center of the plate.

This form of tie plate may be spiked to the wooden tie in the same manner as the 20 larger tie plate or two of these tie plates may be connected together by a tie rod 8 as shown in Fig. 6 in the manner shown and described in my Patent No. 1,349,754 above referred to by the use of a bolt 9 and the 25 wedge plate and locking plate 10 and 11 respectively, thus forming a metallic tie which may be placed upon the road bed, without the use of a wooden tie, and which will prevent creeping or spreading of the rails in 30 the manner above described.

It has been found by actual experience that the sharpened lower edges at the forward ends of the tangs may be best obtained by stamping or punching the tangs cold 35 from the plates which are of considerable thickness, the punching being done in a bottomless die, the lower end of the punch being so constructed that it engages the plate before the portion of the punch which cuts 40 the end of the tang from the plate, the center of the tang being thus punched out before the end of the tang is cut, thus producing a sharpened lower edge at the free end of the tang.

45 I claim:

1. A device of the character described including a pair of tie plates provided with rectangular rail engaging tangs stamped from diagonally opposite corner portions 50 thereof, said tangs being provided with sharpened edges arranged to bite into the

base flange of the rail and a tie bar connecting said plates.

2. A device of the character described including a pair of tie plates provided with 55 rectangular rail engaging tangs stamped from diagonally opposite corner portions thereof, said tangs being provided with sharpened edges arranged to bite into the base flange of the rail and a tie bar connecting said plates, and provided with angular portions to engage the base flanges of the rails, a bolt located through each tie plate and through the tie bar and means upon the bolt for drawing the tie bar and the tie plate 60 65 tightly together to clamp the base flange of the rail therebetween.

3. A railway tie plate provided with rectangular rail engaging tangs stamped from diagonally opposite corner portions thereof 70 and having apertures near opposite edges for the reception of spikes or the like the free ends of said tangs being provided with sharpened edges to bite into the base flange of the rail.

4. A railway tie plate provided with rectangular rail engaging tangs stamped from diagonally opposite corner portions thereof and having diagonally opposed pairs of 80 apertures upon opposite sides thereof for the reception of spikes or the like, the free ends of said tangs being provided with sharpened edges to bite into the base flange of the rail.

5. A railway tie plate comprising a rectangular metal plate having integral, rectangular rail engaging tangs stamped from diagonally opposite corner portions thereof, the free ends of the tangs being provided with sharpened edges and provided with apertures at opposite ends for the reception of spikes or the like, said tie plate being adapted to be placed diagonally beneath the base flange of a rail and driven into position thereon, the sharpened edges of the tangs being arranged to bite into the base flange of the rail to prevent creeping of the rail when the tie plate is attached to a tie.

In testimony that I claim the above, I have hereunto subscribed my name.

ELMER E. FOX.
